UNITED STATES PATENT OFFICE

136,093

DESIGN FOR A BILLFOLD

Herman Weinstein, New York, N. Y.

Application May 18, 1943, Serial No. 110,232

Term of patent 3½ years

To all whom it may concern:

Be it known that I, Herman Weinstein, a citizen of the United States of America, residing in New York city, county of New York, and State of New York, have invented a new, original, and ornamental Design for a Billfold, of which the following is a specification, reference being had to the accompanying drawings, forming part thereof.

Fig. 1 is a front view of a billfold showing my new design.

Fig. 2 is a rear view of the billfold as shown in Figure 1, with the rear flap in opened position.

Fig. 3 is a front view of the billfold as shown in Figure 1, illustrating the flap portion in open position.

I claim:

The ornamental design for a billfold, substantially as shown.

HERMAN WEINSTEIN.
